UNITED STATES PATENT OFFICE.

WINFIELD E. HINSDALE, OF NEW YORK, N. Y., ASSIGNOR TO THE HENRY HUBER COMPANY, OF NEW YORK, N. Y., A CORPORATION OF WEST VIRGINIA.

CLOSET-JOINT.

SPECIFICATION forming part of Letters Patent No. 760,863, dated May 24, 1904.

Application filed April 30, 1903. Serial No. 154,996. (No model.)

To all whom it may concern:

Be it known that I, WINFIELD E. HINSDALE, a citizen of the United States, and a resident of the borough of Manhattan, city, county, and State of New York, have invented certain new and useful Improvements in Closet-Joints, of which the following is a specification.

This invention relates to improvements in closet-floor joints, the object being to provide a floor connection between an earthenware water-closet or like fixture and the soil or other waste pipe which will result in a perfectly tight and permanent joint between the parts.

A further object is to so construct the parts that the setting up of the closet does not require any particular skill in the art, but may be accomplished by any workman of ordinary intelligence.

A further object is to avoid the use of bolts, screws, or other external fastenings through the earthenware foot, and thereby render the joint trim and sightly.

25 Closet-bowls are usually set or mounted upon a marble or other slab, the end of the soil-pipe being extended up through an opening in the slab and joined to the bowl at its foot. The difficulty of making a satisfactory

30 union of the metallic pipe and earthenware bowl has hitherto engaged the attention of plumbers and others familiar with the art, and several forms of connection have been proposed which were designed to make a durable liquid and gas tight joint which would at the same time permit the subsequent removal and replacing of the closet. It has been proposed, among other constructions, to solder to the upper end of the soil-pipe a brass

35 or other coupling which is interiorly screw-threaded and is designed to receive a screw-threaded sleeve which is bolted to the under side of the closet-foot, so that the sleeve forms, essentially, a part of the closet. In this construction the closet is designed to be bodily re-

40 volved to connect the two parts. While a joint which is satisfactory in some respects is attained by this construction, yet there are certain attendant disadvantages which result

from its use. The chief objection has been 50 that when the closet was screwed down so that its flange rested firmly upon the floor or slab it was very apt to assume a position which was not in correct alinement. This has necessitated unscrewing the closet until such 55 correct position was reached, thereby raising the foot of the closet and filling or packing the space thus left between the foot of the closet and the slab with cement or other material. Another objection has been that unless the coupling was fixed to the waste-pipe with its vertical axis exactly perpendicular to the slab it was impossible to screw the closet home at all. It has been necessary, therefore, that the greatest care be taken in 60 the manufacture of the various parts, which has involved the fitting together of each closet and its accessories at the factory and the placing of indicator-marks, &c., upon the complementary parts for the guidance of the 65 workman in setting up the closet. Even under these circumstances any unevenness of the parts could not well be compensated for, so that the bowl was not certain to rest firmly upon the slab when in place. My invention 70 avoids these several objections, while introducing certain important advantages over the constructions heretofore used.

To this end in the preferred construction of my invention I provide a coupling of brass 80 or other metal, which is soldered or otherwise united to the end of the soil-pipe, as heretofore, and I provide a floor-plate which is formed with a wide lateral flange surrounding the soil-pipe and which is also formed 85 with a depending screw-threaded discharge-pipe connection, forming a continuation of the discharge-opening of the closet. The plate is designed to screw into the discharge or soil pipe coupling until the under side of its flange 90 rests firmly against the top of the closet-slab. The floor-plate thus constitutes, essentially, a part of the discharge-pipe and is entirely independent of the closet-bowl until the latter is set in place. The upper face of the flange 95 is formed with a series of vertically-projecting concentric flanges or rings, preferably three in number, so that there are left between

them two annular grooves. The flanged foot of the closet-bowl is formed upon its under surface with grooves corresponding to the rings upon the floor-plate, so that the latter enter such grooves when the closet is in place. The walls of the grooves and rings are so formed that when the spaces between them are filled with cement they will resist relative rotation of the plate and closet. Preferably this is accomplished by providing the opposing parts with radially-projecting ribs or shoulders. Should it become necessary to remove the closet at any time after the cement has set hard, this may be effected by bodily rotating the closet, thus unscrewing the plate from the coupling, the ribs or shoulders preventing the relative movement of the plate and closet. If the same closet is to be replaced, it is obvious that when it is screwed down it will occupy exactly its former position, and a perfectly-tight joint will again result.

Referring to the drawings, Figure 1 is a view of the lower part of a water-closet embodying my invention, the connection being shown partly in section on the line 1 1 in Fig. 2 and partly in elevation. Fig. 2 is a view showing at upper left hand a horizontal section on the line 2 2 in Fig. 1 and at lower right hand a plan of the floor-plate, and Fig. 3 is an under side view of a part of the closet-foot.

Referring to the drawings, let A designate the lower part of an earthenware closet-bowl having a flanged foot B, which rests upon the usual slab of marble or slate C. The under side of the flange B is usually ground or otherwise trued at *a*, so as to rest firmly and evenly upon the upper face of the slab C. The latter is apertured at *b*, so as to afford passage for the discharge or soil pipe D.

E is a coupling of brass or other suitable metal, which is designed to fit into the upper end of the soil-pipe D, the latter when of lead being enlarged to receive a shoulder *c*, formed upon the exterior of the coupling. To make an absolutely gas and liquid tight union between the coupling and pipe, the parts are usually soldered together, as shown in Fig. 1.

F is a floor-plate, which is formed with a tubular connection *d*, which is exteriorly threaded to screw into the coupling E. The plate F is also formed with a wide lateral flange *e*, the lower outer edge of which is preferably ground or machined to a true plane, so as to rest evenly upon the slab C, as shown at *f*. After the coupling E has been soldered to the soil-pipe D the plate F is screwed down firmly in place, so that a leak-tight joint is made between the parts, and the flange *e* rests firmly upon the closet-slab. The foot B of the closet is designed to be secured to the flange *e* of the plate F after the plate is screwed home as just described, and my invention provides

for thus uniting the closet and plate by the use of a cement or other adhesive. To afford a large area of adhering-surface for the cement, I form the upper face of the plate F with several concentric flanges or rings—preferably three, *g*, *h*, and *i*, as shown—these rings entering within corresponding grooves *j*, *k*, and *l*, formed in the under side of the flange B. The rings and grooves are so formed that their contours are non-circular, so that at least a part of their surfaces will present sufficient irregularity to resist rotation of the parts when the cement filling has hardened between them. By preference the rings of the plate are formed with ribs or projections *m*, and the walls of the grooves of the flange B are formed with corresponding ribs *n*, as best seen in Fig. 2. The rings and grooves of the plate and flange do not make contact, but are so formed that there are left between them spaces for the cement filling *o*, the preferred proportions being such that the projections *m* and *n* are quite widely separated, as shown in Figs. 1 and 2, so that the closet may be freely rotated when in place before the cement sets or hardens. The spaces between the rings or flanges and grooves should be such as to contain a sufficient quantity of cement to securely hold the parts together. My invention provides for such a relative proportioning of these spaces and the two grooves formed between the rings of the plate that such grooves shall contain sufficient cement to substantially fill the spaces above referred to. The annular space *p* between the ring *i* and the outer wall of the groove *l* constitutes a relief or exuding space for receiving any excess of cement when the closet is fitted in place. The ribs or projections have the effect of increasing the contacting surface for the cement, but are chiefly of importance in that they resist any relative rotation of the closet and floor-plate after the cement is set. To best effect this result, I form these projections with shoulders radially of the plate and flange and with their length approximately perpendicular to the floor. I do not wish to be limited, however, to any particular form or location of them, as any shape or arrangement of the plate and flange may be adopted which will tend to resist relative rotation of the parts after the cement or other filling has hardened. Any suitable cement may be used which will set within a reasonable time; but I have found that the well-known mixture of litharge and glycerin is well adapted for this purpose.

The operation of setting up a closet according to my invention is as follows: The coupling E is first secured to the upper end of the soil-pipe by soldering or otherwise. The coupling should not be soldered in place until the workman has assured himself that its axis is perpendicular to the slab, as by screwing down the floor-plate, the latter being then

unscrewed and the coupling soldered fast. The floor-plate is then screwed down permanently. During these two operations no attention need be paid to the angular positions assumed by the coupling and floor-plate, it being only necessary that the plate shall be screwed down to a firm and even bearing upon the slab. The spaces or grooves in the upper surface of the floor-plate are next filled with cement, and the flange B of the closet is then fitted in place and the closet forced down until its foot rests evenly upon the slab. As the rings of the flange enter the grooves of the plate a portion of the cement is forced from the grooves until it is spread evenly between the parts in the spaces left for this purpose. The closet may be freely turned until it has been placed in its proper position, the cement affording no resistance to such movement when in its plastic condition. After the cement has hardened, however, there is formed between the two parts not only a non-rotative mechanical connection, but an efficient liquid and gas tight seal which effectively prevents any leakage through the joint. As the faces *a* and *f* of the closet-foot and floor-plate are ground or otherwise formed in true planes, it is obvious that when the closet is set up all parts of the fitting will be brought into correct relative positions with the vertical axis of the threaded parts exactly perpendicular to the plane of the slab.

Several advantages incident to my invention will be at once apparent. The use of all instruments of precision or indicator-marks, &c., are avoided, so that the manufacturer may place the closet and its fittings upon the market without previously assembling them or using special care in their manufacture. The necessity for skilled workmanship is avoided, as the closet may be set up by any one of ordinary intelligence. No particular care is required in the fitting of the coupling to the soil-pipe nor in the screwing of the floor-plate to the coupling, as no matter what angular position the floor-plate assumes at the end of its rotation such position has no effect upon the proper location of the closet. It is only necessary that the floor-plate shall rest in a substantially even manner upon the slab. The entire absence of bolts or similar fastening means between the closet and floor-plate is a notable feature of my invention. The parts may be more cheaply and strongly constructed, and no part of the connection is visible when the closet is in place. The separate parts are shipped to the user, who assembles them in the manner before described.

When my invention is used in connection with an iron soil or waste pipe, it will be understood that the coupling may be screwed into the pipe instead of being united thereto by a soldered joint, or the coupling may be dispensed with, the floor-plate in this case being screwed directly to the top of the pipe.

It will be seen that my invention involves a novel method of applying the closet to the soil-pipe. This consists, essentially, in first screwing the floor-plate to the soil-pipe and subsequently fastening the closet to the floor-plate without the necessity of rotating the former.

I claim as my invention the following-defined novel features, substantially as hereinbefore specified, namely:

1. The combination of an earthenware closet or similar fixture and a floor-plate, the one having a groove and the other a flange entering said groove, and a filling within said groove, adapted to be introduced when in a plastic condition, and to subsequently harden, said fixture and plate being formed with a space between them to hold said filling in its plastic condition when in their upright positions during the operation of setting up the fixture, the walls of said fixture and plate forming said space being non-circular so as to prevent rotative displacement when the filling has hardened, and said walls being spaced apart sufficiently to permit such rotative displacement when the filling is in its plastic condition.

2. The combination of an earthenware closet or similar fixture and a floor-plate, said floor-plate being formed upon its upper surface with upwardly-extending flanges forming a channel between them, and said fixture having grooves within which said flanges extend, and a filling within said channel, adapted to be introduced therein in a plastic condition when the floor-plate is in place, and to subsequently harden therein, the walls of said grooves and flanges being non-circular so as to prevent relative rotation of said fixture and plate when said filling has hardened, and being spaced apart sufficiently to permit such rotation when the filling is in a plastic condition.

3. The combination of an earthenware closet or similar fixture, a coupling adapted to be connected to the discharge-pipe, and a floor-plate, said floor-plate being formed upon its upper surface with upwardly-extending flanges forming a channel between them, and said fixture having grooves within which said flanges extend, and a filling within said channel adapted to be introduced therein in a plastic condition when the floor-plate is in place, and to subsequently harden therein, the walls of said grooves and flanges being spaced apart sufficiently to permit relative rotation of said fixture and plate when said filling is in its plastic condition, and being non-circular, so as to prevent such rotation when the filling has hardened, and said plate and coupling having engaging means for fastening them together.

4. The combination of an earthenware closet having a flanged foot, said foot having a series of concentric grooves formed on its under surface, and being formed with radial

projections extending within said grooves, a floor-plate having a series of rings upon its upper face adapted to fit loosely within said grooves, said rings having projecting portions 5 opposite those of the flange, and a filling between the walls of said rings and grooves.

5. The combination of an earthenware closet having a flanged foot, said foot having a series of concentric grooves formed on its under surface, said grooves being formed with radial projections, a floor-plate having a series of rings upon its upper face adapted to fit loosely within said grooves, said rings hav-

ing projecting portions opposite those of the flange, a cement filling between the walls of 15 said rings and grooves, a screw-threaded connection formed on said floor-plate, and a coupling fixed to the discharge-pipe and engaging said connection.

In witness whereof I have hereunto signed 20 my name in the presence of two subscribing witnesses.

WINFIELD E. HINSDALE.
